SENSITIVITY IMPROVER FOR TEMPERA-
TURE CONTROLLERS

Charles Alfred West, Southbridge, Mass.

Application May 26, 1948, Serial No. 29,288

1 Claim. (Cl. 236—99)

1 This invention relates to a mechanism adapted to improve the sensitivity of mechanisms heretofore used for performing a mechanical operation such as opening or closing a valve under the automatic control of a temperature responsive device.

It is the general object of my invention to improve the construction of such mechanisms as heretofore known in such manner as to provide more rapid response, a higher sensitivity and more satisfactory operation.

My invention further relates to arrangements and combinations of parts which will be herein-after described and more particularly pointed out in the appended claim.

A preferred form of the invention is shown in the drawings in which

Fig. 1 is a part sectional side elevation of a controller embodying my sensitivity improver.

Fig. 2 is a sectional plan taken along the general line 2—2 of Fig. 1 showing detail construction to be described.

Referring to Fig. 1 of the drawings the actuating mechanism includes a hood 3 having a depending open chassis frame 6 adapted to be mounted on a valve 14 of any suitable description provided only that the valve may be opened and closed by axial movement of a valve stem 16 slidable in a gland 15 of a stuffing box of a valve 14. A temperature responsive fluid-filled device B is connected by a capillary tube 2 and a passage 29 in a hub 52 to a pressure chamber A between a cup 50 and a bellows 51 and hub 52. The varying downward pressure on the cup 50 and the attached operating stem 4 due to the varying temperature in the device B is opposed by the upward spring pressure of a coil compression spring 7. The valve stem 16 is screwed into a rotatable internally threaded plunger 18 with an integral rectangular boss at its lower end and the valve stem 16 may be secured in axially adjusted position by a locknut 17. The plunger 18 is slidable in a sleeve 19. The sleeve 19 is slidable in a collar 20 screwed into the lower end of the operating stem 4. The upper end of the sleeve 19 is equipped with a tubular nut 22 screwed thereto. The nut 22 is normally held by a spiral compression spring 22a against the upper end of the collar 20 which acts as a stop. The upper end of the spring 22a engages a fixed stop 55. The operating stem 4 is attached to the bellows cup 50 inside the hood 3. The lower end of the operating stem 4 is guided by a collar 21 which is fixed in the lower end of a hollow

adjusting screw 5. An adjusting nut 9 is used for adjusting the compression of the coil compression spring 7. 8 is a section of one arm of the depending chassis frame 6.

2 5 is a frame cross-bar into a central aperture of which the hollow adjusting screw 5 is fixed. The operating stem 4 attached to the bellows cup 50 necessarily travels the same distance as the bellows cup. In the self-acting controllers 10 heretofore used the valve stem also travels the same distance as the operating stem. The added mechanism of my invention now to be described increases the travel of the valve stem 16 so that its travel is very considerably greater than the travel of the operating stem 4 and the bellows cup 50. The rectangular boss at the lower end of the plunger 18 is provided on two opposite sides with horizontal threaded spindles 36. These two spindles act as pivots for two levers 28 and 20 25. These two levers are provided at their outer ends with rollers 26 and 34. The two rollers pass with a small working clearance into two rectangular holes 33 and 38 in the two depending arms of the chassis frame 6.

25 25 At the lower end of the sleeve 19 is a horizontal rectangular bar 23 integral with it and extending outwards almost to the two depending arms of the chassis frame. Each end of the horizontal bar 23 is provided with a vertical slot 30 which extends from the end almost to the sleeve 19. In the lever 28 and half way between the center of the roller 34 and the spindle 36 a small hole 27 to suit a small wire spindle is drilled and vertically above this in the horizontal bar 23 and 35 equidistant from the axis of the operating stem 4 a similar hole 37 is drilled. A connecting link 24a with corresponding pivot holes is assembled with its pivots. A similar connecting link 24 is inserted and pivoted at corresponding points 27a and 31a on the other lever 25 and the bar 23. If the operating stem 4 moves upwards or downwards the bar 23, the two links 24 and 24a and also the two pivots 27 and 27a will move through the same distance (neglecting any slight difference due to the very small angular motion of the links 24 and 24a).

50 The level of the two outer ends of the two levers 25 and 28 is kept constant by the two rollers 26 and 34, but the inner ends swivelling on the two spindles 36 move through twice the distance moved through by the operating stem 4. This also applies to the plunger 18 and to the valve stem 16 attached thereto, so that the valve stem travel is twice that of the operating stem 4, or the ratio of the two is 2:1.

It will be obvious that by transferring the links 24 and 24a to other positions such as 60 and 61 equidistant from the central axis of the operating stem 4, other ratios within limits can be employed.

In Fig. 2 I have shown a horizontal section along the general line 2—2 of Fig. 1 to make more clear the structure of the lever construction for increasing the sensitivity of the instrument. The two levers 25 and 28 are shown double with distance pieces w and y between them so as to provide slots for the four pivoted members 26, 34, 24 and 24a.

The two levers 25 and 28 swivel on the two spindles 36, the two spindles being provided with nuts and locknuts which are adjusted so as to allow the two levers to swivel freely. The two levers 25 and 28 are shown with bent inner ends to clear the rectangular boss at the lower end of the plunger 18. 16 is a section of the valve stem 16 of Fig. 1 which is screwed into the plunger 18. It will be seen from Figs. 1 and 2 that my invention enables the sensitivity of the controller to be considerably increased and therefore it also increases the speed of response and the efficiency of the controller generally. It also increases the available overall travel of the valve stem without imposing increased and deleterious flexing of the bellows thus favoring a longer life for the bellows, and it also enables the controller to be used with valves requiring a longer valve stem travel than is otherwise practicable.

Having thus described my invention and the advantages thereof, I do not wish to be limited to the details herein described other than as set forth in the claim, and what I claim is:

The combination of a sensitivity improver and a temperature controlled actuating mechanism for moving, by means of the said sensitivity improver, the valve stem and valve disc of a valve, the said mechanism being under the control of a fluid filled device which is responsive to temperature changes, the said mechanism including a chassis composed of a cylindrical hood and a depending open frame with two vertical side arms, arranged for assembly to the said valve, the said fluid filled device comprising an expansible fluid pressure container and a bulb connected thereto by a capillary tube, the said container, tube and bulb being charged with a temperature responsive fluid, the said expansible fluid pressure container including an upper stationary member centered by a spigot to the top of the said hood, the cup or lower movable member of the said container having centrally attached thereto a tubular operating stem, the fluid pressure in the said container varying with the temperature in the said bulb but always tending to

move the said cup and the attached operating stem in a downward direction, a heavy compression coil spring mounted so as to always tend to move the said cup of the said expansible fluid pressure container in an upward direction or towards a collapsed position, the resultant upward or downward force of the combination of the said spring and the said expansible fluid pressure container operating on the said cup with its tubular operating stem, the said operating stem being provided with a collar fixed into the interior of its lower end, the said operating stem being operatively connected to the said valve stem by means of the said sensitivity improver, the said sensitivity improver including a tubular sleeve, freely slideable in the said collar, a hollow tubular nut screwed to the upper end of the said sleeve and acting as a stop, normally pressed by a compression coil spring into contact with the upper end of the said collar, the said tubular sleeve being provided at its lower end with a horizontal rectangular bar extending outwards almost to the said two depending arms of the said chassis, a tubular plunger freely slideable inside the said sleeve, the said plunger being threaded internally and screwed to the said valve stem, and also provided at its lower end with a rectangular boss which carries on each of two opposite sides a horizontal spindle, two levers swivelling on the said two spindles, the outer ends of the said two levers each carrying a pivoted roller, the said two rollers entering two rectangular holes, one in each of the said two depending arms of the said chassis, the center points of the said two levers being pivoted to the lower ends of two links, the upper ends of the said two links being pivoted to the said horizontal bar, all the four pivots at both ends of the said two links being equidistant from the axis of the said operating stem, and also means for altering the positions of the said pivots at the ends of the said two links and thus varying the mechanical advantage between the said operating stem and the said valve stem.

CHARLES ALFRED WEST.
